UNITED STATES PATENT OFFICE.

HENRY LACASSE AND SOL. WILE, OF ROCHESTER, NEW YORK, ASSIGNORS
TO THE BOTTLERS' SPECIALTY COMPANY, OF SAME PLACE.

TWISTING MECHANISM.

SPECIFICATION forming part of Letters Patent No. 443,192, dated December 23, 1890.

Application filed November 5, 1889. Serial No. 329,352. (No model.)

To all whom it may concern:

Be it known that we, HENRY LACASSE and SOL. WILE, of Rochester, in the county of Monroe, in the State of New York, have invented 5
new and useful Improvements in a Twisting Mechanism, of which the following, taken in connection with the accompanying drawings, is a full, clear, and exact description.

Our invention relates to an improved twisting mechanism, and has for its object the production of a simple and effective device which rapidly and effectively twists together separate strands of wire or other material; and to this end it consists, essentially, in a 10 revolving spindle, twisting-arms pivoted to said spindle and rotated thereby, and a sliding collar upon the spindle connected to the said twisting-arms for approximating their impinging faces.

It consists, furthermore, in the peculiar operating mechanism for said twisting device, the cutter for clipping off the twisted wire, and the detail construction and arrangement of the parts, all as hereinafter more particularly described, and pointed out in the claims.

In describing this invention reference is had to the accompanying drawings, forming a part of this specification, in which like letters indicate corresponding parts in all the views.

Figure 1 represents a plan view of our improved twisting mechanism as shown in operative position upon a portion of the frame of a machine for corking bottles and wiring the corks thereto, with part of the mechanism of said machine in operative position in relation to our twisting mechanism. Fig. 2 is an elevation of the parts as shown in plan in Fig. 1, with the exception that the corking and wiring mechanism is not illustrated. Fig.

3 is an elevation, partly in section, illustrating particularly the construction of the twisting-arms, their position when locked upon the wire, and the cam for operating said arms. Fig. 4 is an elevation, part thereof being

broken out, of the cutter of our twister and its operating mechanism. Fig. 5 is a plan view illustrating in detail the cutter illustrated in elevation in Fig. 4. Fig. 6 is a vertical sectional view taken on line xx , Fig. 1.

Fig. 7 is a sectional view taken on line yy , Fig. 6. Fig. 8 is a horizontal sectional view

taken on line zz , Fig. 6. Fig. 9 is a perspective of the detached lower extremity of the twisting arms or jaws, and Fig. 10 is an elevation of a bottle before being operated upon by our improved twister.

The supporting-frame A illustrated in the drawings is that of a machine for corking bottles and wiring the corks thereto, substantially as illustrated and described in our pending application, Serial No. 319,355; but it will be understood that the supporting-frame may be of any desirable form and construction necessitated by the particular form of mechanism mounted thereupon and to which our twister is connected.

Rising from the frame A is a suitable standard B, having the extending plate or arm B' , in which is mounted the support C for the twisting arms or jaws D. This support C is preferably revoluble in a bracket B^4 , mounted on the plate B' and is prevented from end-wise movement by means of the hub C' , having the double flanges c and c' , which bear against shoulders provided in said plate. In order to allow of the ready securing and removing of this hub, we prefer to use a cap B^3 , secured to the plate B' by screws b and fitting between the shoulders c and c' of the hub C . The twisting arms or jaws D are mounted in a slot or cut-out c' in the hub C' , and are formed with their free extremities D' normally held apart, in order that the wire or other article to be twisted may be readily placed between them. As best seen in Fig. 9, the ends D' of the twister-arms are formed with the inward extensions or arms D^2 , provided with the inwardly-extending cut-out D^3 . When approximated, these arms D^2 lie one above the other, and the wire is thus interposed between the inner side d of the separate cut-outs D^3 .

Provided at the upper part of the spindle C is the upward projection C^2 , upon which is mounted a sliding sleeve E for approximating and separating the impinging extremities D^3 of the twisting-arms. This sleeve E is connected to the upper extremity of said arms D by means of links F, pivoted thereto at f and to the separate twisting-arms at f' . It will thus be seen that when the sleeve is raised upward the links F are raised into a

vertical position, separating the lower extremities of the twisting-arms, and when the sleeve is forced downward the links are then straightened into a horizontal plane, as illustrated in Fig. 3. By thus straightening the said links F the twisting-arms have no tendency to separate when locked upon the wire; but are firmly held in their impinging position.

- 10 Although the sleeve E may be raised in any desirable manner, we prefer to use a yoke or lever G, pivoted at g to a suitable supporting-bracket G', mounted upon the plate B' or other suitable support. This yoke is provided with projecting studs or rollers g' , which engage a groove f^2 in the sleeve E, and thus serve to raise and lower the same and allow the sleeve to revolve freely without affecting the position of said yoke.
- 15 Motion is preferably conveyed to the yoke G by means of a lever H, which in our improved machine, heretofore referred to, serves also to operate the compressor.

Secured to the pivotal spindle of the lever 20 G is the arm G^2 , pivoted at g^2 to a suitable link I, pivoted at h to the crank-arm II', formed upon the pivotal pin of the swinging lever II. Pivoted to said lever II at h^2 is a suitable link or other connection J, hinged at 25 j to a suitable lever K, loosely pivoted or mounted on a spindle or shaft k , mounted in a bracket L.

At the pivotal point j of the lever K and the link J is the bearing-point j' , which preferably consists of a roller, against which bears a cam M, mounted upon a shaft m , suitably supported upon the frame A and preferably by the bracket L. This cam M is revolved in the direction indicated by the arrow and 30 forces upward the lever K, and by the connecting-links and levers previously described forces downward the collar E and approximates the lower extremities of the twisting arms.

35 As illustrated, this operating mechanism is substantially the same as that shown in our pending application for compressor mechanism, and it will be understood that in order to reduce to a minimum the number of parts in 40 our improved machine for corking bottles and wiring the corks thereto, of which this twisting mechanism forms a part, we prefer to utilize the lever II to operate both the compressor and the sleeve E. It will, however, be understood that, if desired, the arm G^2 might be connected directly to the lever K without the use of the rocking lever H. The operating-face m' of the cam M is of sufficient length to cause the parts to remain in their described 45 operative position until the completion of the twisting, after which a stud or roller m^2 , formed upon said cam, contacts with a face K', formed upon the lever K, and retracts said lever, so that the roller j' registers with a cut-out m^3 in said cam. Immediately after the impinging of the twisting arms or jaws upon the wire or other article to be twisted

50 the spindle C is rotated, and after the completion of this rotation the twisting-jaws are separated by the retraction of the lever K, as previously described.

55 The rotating mechanism may be of suitable construction, but preferably consists of gearing or other power-transmitting mechanism between the shafts C and m . At the upper extremity of the sleeve C we provide a bevel-gear N, which meshes with a like gear N' , mounted upon a shaft n , supported by suitable brackets n' , one of which is mounted on the supporting-bracket B' of the shaft C and 60 the other upon the table A. Provided at the opposite extremity of the shaft n is a bevel-gear n^2 , connected to a like bevel-gear O, mounted upon the shaft O'.

65 As preferably constructed, our twisting mechanism is operated intermittently from the continuously-revolving shaft m , which communicates motion to the shaft k by the gears M' and k' , secured to the respective shafts.

70 Mounted on the shaft k is a gear k^2 , meshing with a gear O^2 , loosely mounted on the shaft O', to which it is intermittently locked by a clutch (not illustrated) operated by a suitable cam (also not illustrated) and mounted on either of the continuously-rotating shafts m or k . If desired, this clutch and cam might be the same as those illustrated and described in our pending application for improved wiring mechanism, and it will be understood that at the time when the bottle is 75 registered with the twisting mechanism the gear O^2 is automatically locked to its shaft and the twisting immediately commences. After the twisting the gear O^2 is unlocked 80 and the twisting ceases.

85 It will also be understood that the said twisting device and the operating mechanism for locking the twisting-arms upon the wire are also relatively timed with each other, in order that when the twisting commences the arms may be locked upon the wire and when the twisting ceases the arms may be unlocked 90 from the wire.

95 In order to produce a neat and uniform 100 finish to the wired bottles, it is desirable to cut or clip off the extremities of the wire, since it frequently happens that the projecting strands when twisted together are not of the same length and one or more project above 105 the others. This desirable object we accomplish by means of the cutting mechanism P, (best illustrated in Figs. 3, 4, and 5,) and which preferably operates just before the completion of the twisting to sever the wire at a 110 point somewhat below the twisting-jaws. The preferable construction of this cut-off mechanism consists of a pair of levers or plates Q and R, hinged to each other at r and provided with cutting-jaws R', shearing past one another. The lever or arm Q is loosely mounted upon a pivotal pin S, supported in a journal-bearing B' of the plate B'. The opposite arm R is pivoted at R^2 to a lever T, firmly secured 115

90

95

100

105

130

to the pivotal pin S. By reference to Fig. 5 it will be noticed that the pivot-point of the lever T works in a slot r' of the plate R, and thus enables the said plate R and lever T 5 to be straightened from their normal toggle-shaped position.

As presently described, the cut-off is swung into operation beneath the twisting-jaws, and motion is transmitted to the loose lever or 10 plate Q by means of a spring r^2 , which bears against said lever or plate and is secured to the lever T. When these levers are in operative position, the spring allows the jaw of the 15 cut-off plate R to shear by the jaw of the loosely-mounted plate Q, as presently described. This cut-off is normally swung from beneath the twisting arms or jaws and is forced into position by means of the rocking or partial turning of the pin S. At the upper 20 part of said pin is the lever U, pivoted at u to a connection u' pivoted at u' to a lever W. This lever W is preferably pivoted to or loosely mounted on the spindle or shaft k , and is provided with the downwardly-de- 25 pending portion W', formed with the oppositely-arranged bearing-faces w and w' , against which contacts a roller m^4 , provided upon the gear M^2 , mounted on the shaft m . As this roller contacts with the upper face w , 30 it forces forward the upper portion of the lever W and rocks the cutter into a position beneath the twisting arms or jaws. Just before the disengagement of the face w and the roller m^4 the cut-off levers Q and R catch the 35 twisted wire at the point r^3 , whereupon the forward movement of the loose lever Q is stopped by reason of a suitably-arranged stop Q', preferably consisting of a strong spring-bar mounted on the journal-bearing B³. During 40 the remaining movement of the arm W the pivotal pin S is further rocked around, and the arm T forces forward the cutting-jaw formed upon the lever R and operates the same to shear by the cutting-jaw formed upon the lever Q, and thus cut off the wire. This additional movement of the lever R is allowed 45 by reason of the slot r' and the spring r^2 , previously referred to, which is thus compressed, and afterward retracts said cutting-jaws to 50 their normal position, when the wire is severed. Immediately after the disengagement of the roller m^4 from the cam-face w the said roller contacts with the lower face w' , and the cut-off is then retracted. As previously 55 described, there remains a slight movement of the twisting mechanism after the operation of the cut-off in order that we may positively insure the twisting of the wires to and preferably above the point at which the cut-off 60 operates.

In order that a fine finish may be given to the bottles, we prefer to lay or flatten the wire upon the top of the cork. This result is effected by a rounded or other suitably-shaped 65 projection r^4 upon the underneath side of the cutting levers or knives. As preferably con-

structed, this projection consists of a rounded head r^4 upon the common pivotal pin of said knives. In order to bring about this result the cutter registering or operating mechanism is so timed that after the severing of the wire 70 said knives are given a slight forward movement, which is allowed by the yielding of the spring-stop Q' and is sufficient to cause said projection r^4 to lay the projecting wire. 75

The operation of our invention will be readily perceived from the foregoing, and it will be understood that a bottle wired as illustrated in Fig. 10 is supported so that the upwardly-projecting strands of wire will be 80 readily engaged by the twisting-arms, which are then in their open position. The cam M then approximates said twisting-arms together, securely locking the same upon the wire, and immediately the twisting mechanism is brought into operation, thus rotating the twisting-arms and twisting the projecting 85 extremities of the wire. Just before the stoppage of the rotation of the twisting-arms the cutter is brought into operation and trims off 90 the top of the wire, and is then forced forward to lay the twisted extremities of the wire down upon the top of the cork. 95

It will also be understood that we do not limit our twisting mechanism to the operation upon bottles wired in the manner illustrated, since it will be understood that it would be equally serviceable in other styles of wiring. 100

As considerable change may be made in the relative construction and arrangement of the parts of our invention without departing from the spirit thereof, we do not wish to be limited to its precise form and construction. 105

Having thus fully described our invention, what we claim as new, and desire to secure by Letters Patent, is— 110

1. In a twister, the combination of twisting arms or jaws, a rotary spindle for revolving said arms, gearing for revolving said spindle, and a loose collar sliding on said spindle for closing the arms upon the wire, substantially as and for the purpose specified. 115

2. In a twister, the combination of a rotary spindle, twisting-arms pivotally supported on said spindle and formed with engaging jaws at one extremity, links pivoted to the opposite extremities of said arms, and a connection between said links movable lengthwise of said spindle, substantially as and for the purpose set forth. 120

3. In a twister, the combination of the twisting arms or jaws, a rotary spindle, means for revolving said spindle, a collar or sleeve sliding on said spindle, and links connecting said collar and arms, substantially as set forth. 125

4. In a twister, the combination of twisting-arms having jaws at one extremity, a rotary spindle for supporting said arms, a connection between the opposite extremities of said arms, mechanism for moving said connection lengthwise of said spindle, a cut-off 130

for cutting off the wire, and connected mechanism between the foregoing parts, substantially as described.

5. In a twister, the combination of twisting arms or jaws, a rotary spindle for supporting said arms or jaws, means for revolving said spindle, a loose sleeve connected to said arms for closing them upon the wire, a cut-off for cutting off the wire, and connected mechanism between the foregoing parts, substantially as specified.

6. In a twister, the combination of twisting-arms having grasping-jaws at one extremity, a rotary spindle for supporting said arms, a connection between the opposite extremities of said arms, mechanism for moving said connection lengthwise of said spindle, a cut-off for cutting off the wire, and connected mechanism between said twisting-arms and cut-off for operating the latter after the commencement of the operation of the former, substantially as and for the purpose set forth.

7. In a twister, the combination of a support, a rotary spindle journaled in said support, twisting arms or jaws pivoted to said spindle, a loose collar movable lengthwise of the spindle and connected to said arms, and a pivoted lever engaging said collar for reciprocating the same upon said spindle, substantially as described.

8. In a twister, the combination of a support, a rotary spindle journaled in said support, twisting arms or jaws pivoted to said spindle, a collar movable lengthwise of said spindle, links connecting said collar and arms, and mechanism, substantially as described, for forcing said links into a horizontal plane when said arms are locked upon the wire, substantially as and for the purpose set forth.

9. In a twister, the combination of a support, a rotary spindle journaled in said support, twisting arms or jaws pivoted to said spindle, a collar sliding on the spindle, links or levers hinged to said arms and collar, a pivoted lever engaging said collar for reciprocating the same upon its shaft, a cam for operating said lever, and connections, substantially as described, between said cam and pivoted lever, substantially as and for the purpose described.

10. In a twister, the combination of a rotary spindle, twisting arms or jaws supported by said spindle, connections between said arms for locking them upon the wire, an oscillating lever K, and connections between said lever K and former connections, substantially as and for the purpose set forth.

11. In a twister, the combination of a support, a rotary spindle journaled in said support, twisting arms or jaws pivoted to said spindle, a sleeve sliding on the spindle, links or levers hinged to said arms and collar, a pivoted lever engaging said collar for reciprocating the same upon its shaft, an oscillating lever K, connections between said lever

K and the lever for reciprocating said collar, and a cam for operating the pivoted lever K, substantially as and for the purpose specified. 70

12. In a twister, the combination of a support, a rotary spindle journaled in said support, arms supported by said spindle, a pivoted lever G for approximating and separating said twisting-arms, connections between 75 said lever and arms, the pivoted lever K, connections between the latter and former pivoted levers for transmitting motion from one to the other, an auxiliary cam-face K' upon the lever K for retracting said lever, and a cam M for forcing said lever backward and forward, substantially as set forth.

13. In a twister, the combination of twisting arms or jaws, mechanism, substantially as described, for operating said twisting arms or jaws to twist the wire, cutting-levers sliding one upon the other, cut-off jaws provided upon said levers, mechanism for operating said cutting-jaws, and connected mechanism between said operating mechanisms, substantially as described.

14. In a twister, the combination of twisting arms or jaws, mechanism, substantially as described, for operating said twisting arms or jaws to twist the wire, levers movable toward 95 each other, cutting-jaws mounted upon said levers, a sliding connection between the levers, mechanism for operating said levers, and connected mechanism between said operating mechanisms, substantially as set forth. 100

15. In a twister, the combination of twisting arms or jaws, mechanism, substantially as described, for operating said twisting arms or jaws to twist the wire, a lever Q, loosely mounted on its pivotal pin, a lever R, having 105 a cutting-jaw shearing by the former cutting-jaw, the lever T, fixed to said pin and hinged to the lever R, with a lost motion between said levers, and connected mechanism between said levers Q and R and the twisting arms or jaws, 110 substantially as described.

16. In a twister, the combination of twisting arms or jaws, mechanism, substantially as described, for operating said twisting arms or jaws to twist the wire, a lever Q, loosely 115 mounted on the pivotal pin and formed with a cutting-jaw, a lever T, fixed to said pivotal pin, the lever R, pivoted to the lever Q and hinged with a lost motion to the lever T, a cutting-jaw provided on the lever R, the lever 120 W, having cam-faces w' w', and a connection between the said pivotal-pin and the lever W, substantially as specified.

17. The combination of twisting arms or jaws, mechanism, substantially as described, 125 for operating said twisting-arms to twist the wire, movable cutting-jaws for cutting off the wire, mechanism for moving the cutting-jaws toward and away from the wire, said mechanism having a further movement after the 130 cutting of the wire, and connected mechanism between the foregoing parts, substantially as set forth.

18. The combination of twisting arms or

jaws, mechanism for operating said jaws, movable levers having cutting-jaws for cutting the wire, a yielding connection between said levers, mechanism for moving one of said levers toward and away from the twisting-
5 arms, a yielding stop S for checking the movement of one of said arms to effect the operation of the cutting-jaws and adapted to yield after the wire is cut, and connected mechanism between the foregoing parts, substantially as and for the purpose set forth.

In testimony whereof we have hereunto signed our names, in the presence of two attesting witnesses, at Rochester, in the county of Monroe, in the State of New York, this 10th 15 day of September, 1889.

HENRY LACASSE.
SOL. WILE.
